UNITED STATES PATENT OFFICE.

GEORGE THORP, OF SOUTH BAY CITY, MICHIGAN.

VICE.

SPECIFICATION forming part of Letters Patent No. 286,345, dated October 9, 1883.

Application filed May 10, 1883. (No model.)

To all whom it may concern:

Be it known that I, GEORGE THORP, of South Bay City, in the county of Bay and State of Michigan, have invented new and useful Improvements in Vises; and I hereby declare that the following is a full, clear, and exact description thereof, reference being had to the accompanying drawings, which form a part of this specification.

10 This invention relates to certain new and useful improvements in the construction of vises; and the invention consists in the peculiar construction and arrangement of the parts, whereby a quick and easy adjustment of the 15 parts is obtained, all as more fully hereinafter set forth.

Figure 1 is a side elevation of my improved vise with the jaws closed together. Fig. 2 is a vertical longitudinal section of the same. 20 Fig. 3 is a similar view with jaws opened through the medium of the screw. Fig. 4 is a like view with the movable jaw extended through the medium of the ratcheted slide.

In the accompanying drawings, A represents the body of the vise, which is provided 25 with the stationary jaw V. The body A is provided with a rectangular opening through its entire length to receive the slide C, the under face of which is provided with a ratchet-face, and with which engages the stud or stop D, projecting up through the bottom of the body, such stud being kept in its engagement with the ratchet by the spring-lever E. The slide C has a channel formed in its upper face, 30 to receive the guide-bar F of the movable jaw G. Through this guide-bar F and the foot of the movable jaw the screw H passes, as in the usual manner, the inner end of such screw engaging with a nut, I, rigidly secured in the 35 slide C. The upper face of the body A is slot-

ted to receive a T-headed bolt, K, by means of which the device is secured to the bench, and through the medium of which the vise may be secured to or from the face of the bench and at any angle thereto, if desired.

45 In practice, when it is desired to extend or open the jaws beyond the limit of the screw, the spring-lever is depressed, so as to disengage the stud from the ratchet, which will allow the slide to be drawn out the desired length, 50 when, releasing the spring-lever, the stud engages with the ratchet and prevents the further withdrawal of the slide, while it does not prevent its being pushed in till the movable jaw comes in contact with the work, where it 55 can readily be secured by operating the screw, as in the ordinary manner.

What I claim as my invention is—

1. In combination with the body A and jaw B of a vise, the ratcheted slide C, guide-bar F, screw H, and movable jaw G, the said ratcheted slide being adapted to be advanced or retracted through the body A, substantially as and for the purposes set forth.

2. In combination with the body A and jaw B of a vise, the ratcheted slide C, guide-bar F, screw H, movable jaw G, stud D, and spring-lever E, when constructed, arranged, and operating substantially in the manner and for the purposes described.

3. In a vise constructed substantially as herein described, and in combination with the body A thereof, the T-headed bolt K, adjusted within a slot in the upper face of such body, as a means for adjustably securing the device 75 to a bench, substantially as specified.

GEORGE THORP.
